GARAGE DOOR SUSPENSION MEANS

Oscar F. Stouffer, Spencer, Iowa

Application September 7, 1940, Serial No. 355,847

2 Claims. (Cl. 16—93)

This invention relates to improvements in door constructions of the type commonly used in garages or barns and pertains particularly to a novel and improved construction wherein the door is shifted in opening, to an overhead position.

A primary object of the present invention is to provide an improved overhead door construction which is so designed that the door may be easily shifted to an overhead position from its closed position without having its lower portion swung outwardly from the opening in which it is located, thereby making it possible to easily open the door under conditions which would cause considerable interference with the opening of other types of overhead doors such, for example, as a condition which frequently develops in the winter where snow piles up against the outer side of the door and forms an obstruction to the moving of the door where such door must swing outwardly in being moved to its open position.

Another object of the invention is to provide in an overhead door construction, a novel means of suspending the door and of guiding the lower part thereof whereby the lower part of the door moves straight upwardly or downwardly in the door opening as the door is shifted to opened or closed position.

Another object of the invention is to provide in an overhead door construction, a novel means of supporting the upper part of the door for swinging and sliding movement by which there is eliminated the necessity of bracing the door against twisting or warping when it is held in its opened position.

Still another object is to provide an overhead door construction of such design that when the door is in its opened position, it will be disposed entirely within the building structure of which it forms a part and will not have any portion extending outwardly through the adjacent door opening for exposure to the weather.

The invention will be best understood from a consideration of the following detailed description taken in connection with the accompanying drawings forming part of this specification, with the understanding, however, that the invention is not to be confined to any strict conformity with the showing of the drawings but may be changed or modified so long as such changes or modifications mark no material departure from the salient features of the invention as expressed in the appended claims.

In the drawings:

Fig. 1 is a view in perspective of the door construction embodying the present invention.

Fig. 2 is a detailed view showing the counterbalance weight and guide means therefor.

Fig. 3 is a view in elevation of the hinge pin supporting bracket.

Fig. 4 is a sectional view on the line 4—4 of Fig. 3.

Fig. 5 is a view in side elevation of a runner unit.

Fig. 6 is a view in front elevation of the runner unit.

Referring now more particularly to the drawings, the numeral 1 generally designates a wall structure in which is formed a door opening 2, which is bordered or outlined by the frame 2. This frame consists of the usual sill 3 and side and top jams 4 and 5, respectively.

In accordance with the present invention, each 20 of the vertical or side jams has secured thereto the vertical angle bar 6, one flange of which projects inwardly to form a track 7. The top jamb 5 may be provided with a jamb strip 8 against which the top part of the door 9 abuts when the door is in closed position and when in such position, the lower edge of the door will rest upon the sill 3.

At each side of the door 9 and at the bottom thereof, there is secured to the inside of the door, the bracket 10 which is preferably formed of a strip of angle iron as shown, one flange of the iron being secured flat against the inner face of the door while the other flange extends inwardly and is flush with the adjacent door edge surface.

The lower end of this bracket extends to the bottom edge of the door and adjacent the lower end of the bracket, there is secured in spaced relation with the inwardly projecting flange 11 thereof, a bearing strip of metal 12 which is in spaced parallel relation with the flange 11 and which rotatably supports an end of a hinge pin 13 which is mounted in a suitable opening therein and which extends through an opening in the flange 11. The outer end of this hinge pin carries a slotted head 14, the slot of which is indicated at 15, and slidably receives the adjacent track 7. Secured to the inner side of the top portion of the door frame adjacent each of the vertical sides thereof is an angled supporting arm 16, one end of which is fixed to the frame, so that the major portion of the arm extends horizontally inwardly while the angled portion, which is indicated by the numeral 17, extends upwardly and is secured to the ceiling or a suitable overhead supporting means. One of these arms supports

a single sheave pulley 18 while the other arm supports a double sheave pulley 19.

The numeral 20 generally designates a horizontally arranged track frame which may be formed of tubular material, as shown, and which consists of the two spaced parallel track portions 21 and a connecting bar portion between the tracks, which is indicated at 22. The free ends of the track portions are secured in a suitable manner to the inner side of the door frame 2 between the pulley supporting arms 16 while the inner end of the unit is supported from the ceiling or from a suitable overhead supporting structure by means of the hangers 23, which may be coupled to the overhead support by a threaded sleeve 24 or in any other suitable manner which will facilitate adjusting the elevation of the inner end of the track unit.

The distance between the tracks 21 is such that when they are arranged above the door 9 so that each will be the same distance from the vertical edge of the door, each track will be spaced from such vertical edge a distance equal to approximately one-quarter of the width of the door. This provides for a better balanced connection between the tracks and the top edge of the door 9, which is accomplished through the medium of the runner units 25.

Each of the runner units 25 consists of a clevis 26 which has the two spaced side portions 27 and the intermediate or yoke portion 28, and a hinge 29 consisting of the two pivotally joined leaves 30 and 31. The leaf 31 of each hinge is secured by a bolt 32 or in any other suitable manner to the yoke 28 of the clevis, while the other leaf 30 is secured to the inner side of the door 9 at the top edge thereof and at right angles to such top edge.

Extending between the side portions 27 of the clevis is a pivot bolt 33 on which is rotatably supported between the portions 27, the peripherally grooved roller 34 which rests upon the top of a track 21, the track passing beneath the roller and between the sides 27 of the clevis, as shown. It is preferred that the clevis 26 be formed from strap metal of suitable weight although this is not essential as will be readily understood.

The pulley sheaves 18 and 19 which are supported upon the arms 16, are disposed outside of the track frame or unit 20, so that the cable 35 which is run over the pulley 18 and the cable 36 which is run over one of the pulleys of the double sheave 19, will extend in a straight line from the pulleys downwardly to the brackets 10 at the adjacent sides of the door where they are secured to the brackets by the bolts 37 which are passed through the inwardly extending flanges of the brackets.

Upon the side of the door adjacent which the double sheave pulley 19 is mounted, the other ends of the cables 35 and 36 are secured to a counterbalance weight 38 for the door. The wall adjacent this counterbalance weight 38 has secured thereto the vertical guide rod 39 for the weight which passes through a guide eye 40, which is secured to the weight body. By this arrangement, it will be seen that as the door 9 is raised and lowered, the weight will be made to move along a vertical path without swinging.

As a suitable means for securing the door in closed position, there is provided upon the inner side of the door, the two bolt rods 41

which are mounted in guides 42 and which have their inner ends joined by the rotatable link 43 which is supported upon a suitable shaft 44, which passes through the door and is accessible from the outside. Thus when the shaft 44 is oscillated, the bolt rods 41 will be shifted transversely of the door to engage in or be removed from suitable keeper openings, not shown, which may be formed in the track angle irons 7. 10 Any suitable key controlled means may be employed for locking the shaft 44 against rotation or for securing the bolt rods against movement whereby the door may be readily locked from the inside or the outside.

15 In the overhead door construction herein described, the rocking axis for the door as well as the suspension point or suspension line extending transversely thereof are disposed in close proximity to the bottom edge of the door as a result of which the door when properly counterbalanced by the weight 38 can be shifted to opened or closed position without the expenditure of a great amount of effort and also the mounting of the door in the frame or upon the tracks 7 is such that the lower part of the door will not swing outwardly from the frame as the door is opened and, therefore, no difficulty will be experienced in opening the door even though it may have snow and ice piled against the outer side thereof. Naturally because of this mounting, the door will open regardless of whatever may be pressing against the outside. It will also be readily apparent that because of the mounting, the door when opened will be entirely within the building structure in which it is mounted and, therefore, will not be exposed to the weather. The runner units 25 are spaced apart so that the weight of the door is evenly divided between them, therefore, the door will be kept from sagging when opened.

40 Due to the fact that the pulleys over which the suspension cables pass are at the outer sides of the tracks and are slightly above the tracks, the door when in opened position, will have its bottom edge raised to the very top of the door opening, thus uncovering the opening to its fullest height.

45 What is claimed is:

1. A sliding pivotal guide for a shiftable structure such as a vertically movable door having a track bar secured parallel with one side edge thereof, comprising an angle bracket secured to one face of the door with one side parallel with and in the plane of the said side edge, a second angle bracket secured to the first bracket and having one side in spaced parallel relation with the said side of the first bracket, the said spaced sides of the bracket being provided with aligned openings, a pivot pin having 50 a shank portion extending through and rotatably supported in the openings of the said spaced sides of the brackets, and a relatively long cylindrical head in abutting relation at its inner end with a face of the said side of the first bracket and extending laterally beyond and in perpendicular relation to the adjacent side edge of the door, means at the end of the shank remote from the head for maintaining the shank in position in said openings, and said head having a relatively deep slot cut across its outer end to receive the said track bar.

60 2. A sliding pivotal guide means for a shiftable structure such as a vertically movable door having a track bar secured parallel with one

side edge thereof, a supporting bracket adapted to be secured to said structure adjacent to said one side edge, a hinge pin rotatably supported on said bracket perpendicular to said side edge, and a slotted head forming an integral part of said pin and extending beyond said side edge to slidably receive said track bar, said bracket

5 having a flange portion extending perpendicular to the face of the door on which the bracket is secured, and said slotted head having a diameter greater than the major portion of the pin forming a shoulder bearing against the flange portion of the bracket.

OSCAR F. STOUFFER.
